[57] CLAIM

The ornamental design for a torchiere lamp base, as shown and described.

DESCRIPTION

FIG. 1 is a perspective view of a torchiere lamp base showing our new design;

FIG. 2 is a front elevational view of the torchiere lamp base;

FIG. 3 is the rear elevational view of the torchiere lamp base;

FIG. 4 is a right side elevational view of the torchiere lamp base;

FIG. 5 is a left side elevational view of the torchiere lamp base;

FIG. 6 is a top plan view of the torchiere lamp base; and,

FIG. 7 is a bottom plan view of the torchiere lamp base.

The shade shown in broken lines is for illustrative purposes only.
